UNITED STATES PATENT OFFICE.

ALONZO G. TURNER, OF DURANGO, COLORADO, ASSIGNOR OF TWO-THIRDS
TO FRANK A. KIMBALL AND ALEXANDER LEVY.

DRILL.

SPECIFICATION forming part of Letters Patent No. 499,312, dated June 18, 1893.

Application filed January 9, 1893. Serial No. 457,773. (No model.)

To all whom it may concern:

Be it known that I, ALONZO G. TURNER, a citizen of the United States, residing at Durango, in the county of La Plata and State of Colorado, have invented certain new and useful Improvements in Drills; and I do hereby declare the following to be a full, clear, and exact description of the invention, such as will enable others skilled in the art to which it appertains to make and use the same.

My invention relates to drills, and particularly to that class of drills employed in rock drilling or in the drilling of wells; and my invention consists in the novel construction and arrangement of the parts, as is hereinafter described.

This invention is an improvement upon another drill of my invention, for which there were granted to me Letters Patent No. 480,978, of August 16, 1892.

The object of this invention is to provide a simple automatic device for locking the drill to its drill-rod when these parts are screwed together, so that it may be impossible for the drill to become unscrewed from the drill-rod while within the boring or well, but so arranged that when desired this locking device may be easily and quickly thrown out of operation, and the drill unscrewed. This object is attained in the mechanism herein described and illustrated in the drawings which accompany and form a part of this application, in which the same reference letters indicate the same or corresponding parts, and in which—

Figure 1 is a perspective view of the upper end or head of the drill, and shows the locking bolt which locks the drill to the drill-rod. Fig. 2 is a perspective view of the lower end of the drill-rod, showing the ratchet teeth with which the locking bolt engages. Fig. 3 is a vertical section of the drill and drill-rod joined together, the plane of section passing through the axis of the drill and drill-rod and through the center of the chamber within which the locking bolt works. Fig. 4 is a horizontal section of the drill and drill-rod, the plane of section being perpendicular to the plane of section of Fig. 3, and likewise passing through the center of the chamber within which the

locking bolt works. Fig. 5 is a detail perspective view of the locking bolt. Fig. 6 is an elevation of a catch-pin to be hereinafter mentioned.

In the drawings, A is the drill, and B the drill-rod. The drill A has at its end a projecting boss C, of a smaller diameter than the drill itself, and the drill-rod B has in its end a corresponding recess. Both boss and recess are screw-threaded, so that the drill and drill-rod may be screwed together until their end faces come in contact.

The end face of the drill-rod B is provided with a number of depressed ratchet teeth D. Within the drill A is a longitudinal chamber E, within which chamber slides a locking bolt, F. This locking bolt consists of two parts, viz., the head, f, and the stem, f'. The head f is provided with ratchet teeth corresponding to the teeth of the drill-rod B. The chamber E corresponds in shape with the bolt F, and consists of a longitudinal bore or passage closely embracing the stem f' of the bolt F, thus serving to guide this bolt as it slides back and forth. The upper end of this chamber E is enlarged to receive the head f of the bolt F. The chamber E is most readily formed in the drill by boring in its end several parallel and closely adjacent holes, the center hole being carried down much deeper than the others to form the passage which receives the stem of the bolt F, and after these holes are bored cutting out the webs of metal lying between them.

A spring, G, at the bottom of the chamber E, tends to push outward the bolt F, this movement of the pin being limited by a screw H the point of which projects into the chamber E and works in a slot I in the head of the bolt.

When pushed outward by the spring G the teeth of the bolt F engage with the teeth of the drill rod B, and lock the same, so that it is impossible to turn backward the drill-rod to unscrew it from the drill. By drawing inward the bolt F its teeth are disengaged from the teeth D of the drill-rod, which may then be unscrewed. For the purpose of drawing inward the bolt F there is provided a slot I

in the side of the drill at a point directly over the stem f' , and in this stem f' is a corresponding recess i . When it is desired to draw inward the bolt F a pointed tool is inserted through the slot I into this depression i , so that the point of the tool catches in this depression, and the bolt F may then be pulled back. To hold the bolt disengaged from the teeth of the drill-rod B there is provided a catch-pin, K , working in a radial passage L opening into, but placed slightly to one side of, the chamber E . The position of this pin K and of the passage L within which it works, is clearly shown in Figs. 3 and 4. In the side of the bolt F is a recess M , and the shank of the catch-pin K is cut away at the neck so as to form a shoulder, N , adapted to fit into this recess M and lock the bolt F . This recess M is so situated on the bolt F that when the bolt is drawn inward far enough so as to be free from the teeth D of the drill-rod B this recess M will be opposite the pin K , and a spring O then pushes this pin K upward so that the shoulder N fits into the recess M and holds the bolt F locked.

The head of the pin K should preferably project slightly above the surface of the drill when it is locking the bolt F in the manner just described, so that should it ever happen, through oversight, that the drill and drill-rod, after having been screwed together, should be dropped into the well without first releasing the bolt F and permitting its teeth to engage with the teeth D of the drill-rod B , the head of the pin K will be pressed inward by the sides of the well as the drill enters the well, thus releasing the bolt F , which will then be forced outward by its spring G into engagement with the teeth D of the drill-rod B . Radial holes, O , O , are provided in the drill A , opening into the chamber E at suitable points, so that through these holes any sand which may collect in the chamber E may be removed.

The operation of this device is as follows:— The locking bolt F being in the position shown in Fig. 1, when the drill and drill-rod are screwed together the teeth of the bolt F will engage with the teeth of the drill-rod in such a manner as to make it impossible to unscrew the drill from the drill-rod, but offering no resistance to the screwing together of the drill and drill-rod, the bolt F being depressed as the teeth D pass over it. The drill and drill-rod can thus be screwed together until their end faces are in contact, so that these faces, and not the threads of the screw may bear all the force of the blows delivered by the drill, and the teeth of the drill-rod B engaging with the teeth of the bolt F make it impossible for any turning of the drill in the well to cause the drill to unscrew from the drill-rod. When it is desired to unscrew the drill from the drill-rod, a pointed instrument is introduced through the slot I into the recess i of the bolt F , and the

bolt is then drawn backward until the recess M is opposite the pin K , when the spring O forces the pin K upward until the shoulder N enters the recess M and holds the bolt locked. The drill may now be unscrewed from the drill-rod. When it is desired to release the locking bolt F so that when the drill and drill-rod are again screwed together they may be locked, the pin K is pressed inward, releasing the bolt F , which is then pushed outward by its spring G . It is obvious that while this locking device is especially adapted to securing drilling tools together, it is also adapted to the securing together of any rods or shafting where it is important that the parts shall not become separated while in operation.

Having thus completely described my invention, what I claim, and desire to secure by Letters Patent, is—

1. The combination with a drill and drill rod screwing together end to end, the said drill rod being provided with a concentric series of ratchet teeth on its end, of a spring actuated locking bolt working in a chamber within said drill adapted to engage with the said concentric series of ratchet teeth, means whereby the locking bolt may be withdrawn from the ratchet teeth, and a spring actuated catch pin for locking the bolt in its disengaged position, substantially as described.

2. The combination with a drill and drill rod screwing together end to end, the said drill rod being provided with a concentric series of ratchet teeth on its end, of a spring actuated locking bolt working in a chamber within said drill adapted to engage with the said concentric series of ratchet teeth, means whereby the locking bolt may be withdrawn from the ratchet teeth, and a spring actuated locking pin for locking the locking bolt in its disengaged position, which normally rests below the surface of the drill, and only projects above the surface of the same when holding the locking bolt withdrawn, substantially as described.

3. The combination, with a drill and drill-rod screwing together end to end, and ratchet teeth in the end of the drill rod arranged in a ring concentric with the drill-rod, of a spring-actuated locking bolt working in a chamber within the drill, its end projecting from the end of the drill and provided with ratchet teeth adapted to engage with the ratchet teeth of the drill-rod, means for drawing inward the locking bolt to disengage it from the teeth of the drill-rod, and a spring-actuated catch-pin provided with a shoulder adapted to enter a recess in the locking bolt when the latter is in its disengaged position, and thus to hold the said locking bolt in said position, substantially as described.

4. The combination, with a drill and drill-rod screwing together end to end, of a chamber E within said drill, a locking bolt F working within said chamber, projecting normally from the end of the drill and provided with

ratchet teeth adapted to engage with corresponding ratchet teeth in the end of the drill-
rod, a spring for pressing the locking bolt out-
ward, and a screw H projecting into said pas-
5 sage E and working in a slot h in said bolt,
for limiting the motion of the said bolt, sub-
stantially as described.

In testimony whereof I affix my signature in
presence of two witnesses.

ALONZO G. TURNER.
